US00D830151S

(12) **United States Design Patent** (10) **Patent No.:** **US D830,151 S**
Weinberg et al. (45) **Date of Patent:** **** Oct. 9, 2018**

(54) **HANDLE FOR HAND HELD TOOLS**(71) Applicant: **BESSEY Tool GmbH & Co. KG**,
Bietigheim-Bissingen (DE)(72) Inventors: **Andreas Weinberg**, Filderstadt (DE);
Martin Ruf, Filderstadt (DE)(73) Assignee: **BESSEY Tool GmbH & Co. KG**,
Bietigheim-Bissingen (DE)(***) Term: **15 Years**(21) Appl. No.: **29/594,726**(22) Filed: **Feb. 22, 2017****Related U.S. Application Data**(62) Division of application No. 29/539,908, filed on Sep.
18, 2015, now Pat. No. Des. 808,766.(30) **Foreign Application Priority Data**

Mar. 26, 2015 (EM) 002669499
